PORTABLE POWER DRIVEN HAMMER

Filed Feb. 20, 1940

UNITED STATES PATENT OFFICE

2,293,443

PORTABLE POWER DRIVEN HAMMER

Harold F. Mossberg, New Haven, Conn., assignor
to O. F. Mossberg & Sons, Inc., New Haven,
Conn., a corporation of Connecticut

Application February 20, 1940, Serial No. 319,854

8 Claims. (Cl. 125—33)

This invention relates to power driven hammers and more particularly to a power driven hammer of the portable type having a power driven rotating member and means to convert the rotary movement thereof into a reciprocating movement to actuate a reciprocable tool.

One object of this invention is to provide an improved form of portable power driven hammer.

Another object of this invention is to provide an improved portable hammer of the above nature wherein the shock occasioned by the blow of a reciprocable member upon a tool will not be transmitted to the driving member and its force may be varied by the operator.

Still another object is to provide an improved hammer mechanism having means to readily attach it to, and to detach it from, a standard form of rotary electric drill, or the like.

Further objects are to provide an improved portable power driven hammer of the above nature with; improved means to hold a reciprocable tool in operative position thereto; improved means to convert rotary movement into reciprocable movement; and means to shield the operator from flying chips, and like scrap, formed during the operation thereof.

A further object of this invention is to provide an improved portable power driven hammer which will be relatively inexpensive to manufacture, simple in construction, and which is very efficient and durable in use.

With these and other objects in view, which will appear as the description proceeds, there has been illustrated in the accompanying drawing, one form in which the features and principles of this invention may be conveniently embodied in practice.

In the drawing, wherein like reference numerals designate like parts throughout the several views:

Figure 1 is a side elevational view of a portable power driven hammer embodying the features and principles of this invention;

Figure 2 is an enlarged broken longitudinal sectional view of the principal operable parts of this invention in one position;

Figure 3 is a cross-sectional view taken on the line 3—3 of Figure 2;

Figure 4 is a cross-sectional view taken on the line 4—4 of Figure 2;

Figure 5 is a cross-sectional view taken on the line 5—5 of Figure 2;

Figure 6 is a cross-sectional view taken on the line 6—6 of Figure 2;

Figure 7 is a broken longitudinal sectional view 55

similar to Figure 2 but showing the operable parts thereof in another position in the operation of the device; and

Figure 8 is a detail side view of a part of the device.

Herein the improved portable power driven hammer of this invention is shown arranged to be driven from a rotatable shaft 11, extending outwardly from one end of a casing 12 which houses an electrical motor (not shown) adapted to be energized by being connected to a source of electric power by means of an electrical cable 13 which, in this instance, extends into a handle 14 provided on the casing 12 and thence to the motor.

The shaft 11 and casing 12, in this instance, are parts of a standard form of electrical drill and therefore the shaft 11 has a drill, or like, shank holding chuck mounted upon its outer end.

10 In this instance, the motor casing 12 has an extension 16 in which is housed suitable reduction gearing (not shown). The housing extension 16 has a bearing boss 17 in which the shaft 11 is journaled, and, in this instance, the boss 17 is provided with exterior screw-threads 18, whereby a sleeve 19, having interior screw-thread therein corresponding with the threads 18, may be screw-threaded thereon. In addition to the threads 18, or in place thereof, the sleeve 19 may be detachably secured on the boss 17 by a set screw 10. The chuck 15 is of the usual type having a rotatable sleeve 20 adapted to close the usual jaws in a cylindrical member 21 and actuated by means of the usual wrench (not shown) but which is located in holes 22 in the member 21 and engages gear teeth 23 on the sleeve 20 to rotate the latter and open and close the jaws of the chuck 15.

The above described structure may constitute 40 the power driving means for this invention, but it is to be understood that, in some instances, the motor and gearing in the casings 12 and 16 respectively may be omitted and other means, such as a flexible shaft from a remotely disposed power source (not shown), may be provided to power drive the shaft 11 upon which the chuck 15 is mounted. In such cases the power driven shaft 11 will be journaled in a boss, or member, similar to a combined structure of the boss 17 and the sleeve 19. The means, cooperating with the power driven shaft 11 through the chuck 15, to convert the rotary movement of the shaft 11 into reciprocating movement, whereby a tool, such as a chisel 24, may be reciprocated, includes a hollow open-ended cylindrical casing 25

having a hollow cylindrical stem 26 extending from the closed end thereof and in which the tool 24 may be detachably mounted. A collar, or band, 27 encircles the hollow stem 26 substantially midway of its length to support a cone-shaped sheet metal shield 28.

The shield 28, in this instance, is provided with a cylindrical hub portion 29 adapted to snugly fit over the stem 26 and seat against the collar 27, and has an outwardly and upwardly curved flange, or rim 31 extending about its peripheral edge adapted to catch and hold chips and the like. A window 30 of suitable transparent material is provided in the shield 28 through which an operator may observe the tool 24 and the article being worked upon. Obviously, the entire shield 28 could be made of transparent material. The object of providing a shield 28, is to protect the operator's eyes, face, and head, from flying chips cut from the work, especially if it is disposed overhead, by the tool 24. The shield 28 being readily removed from the stem 26, need not be used when the work is so disposed that the tool 24 is held horizontally, or pointed downwardly.

The hollow casing 25 is open at its end 32 opposite to the stem 26 and is bored out to fit snugly over the sleeve 19. An air inlet 53 is provided in the stem end of the casing 25 and a plurality of openings 49 are formed in its side wall for ventilation and to facilitate oiling. A number of axially directed slots 33, in this instance four, are provided in the casing end 32, and a peripherally directed slot 34 extends from the inner end of each slot 33. Lugs 35, herein four, extend outwardly from the periphery of the sleeve 19 and are adapted to enter the slots 33, when the casing 25 is slipped over the sleeve 19, and then to enter the slots 34, when the casing 25 is rotated upon the sleeve 19, to lock the casing 25 to the sleeve 19. A leaf spring 36, fastened at one end to the casing 25 by a screw 37, extends toward the casing end 32 and, by having its end 38 curved downwardly, is adapted to snap into one of the slots 33 in back of the lug 35, and in the communicating slot 34, to prevent the accidental rotation of the casing 25 with respect to the sleeve 19 whereby these parts might become disconnected.

A cylindrical plunger, or hammer 39, adapted to freely slide and rotate in the bore 41 of the casing 25, has a hammer portion 42, of smaller diameter than the plunger 39, extending from one of its ends, or its front end, into a bore 43 of the stem 26. The plunger 39 has a portion 44 which is reduced in diameter adjacent the extending hammer portion 42 to form a shoulder 45 facing the portion 42. The shoulder 45 is formed to provide, in this instance two, camming surfaces 46 and 47, which are adapted to engage a pin 48 rotatably mounted in the casing 25, when the plunger 39 is rotated, to force it backwardly toward the chuck 15, as shown in Figure 7. The pin 48 is journaled in a boss 49, provided on the casing 25, and extends through the same and has an annular groove 51 in its outer end, wherein a spring washer 52 is seated to retain the pin 48 in the boss 49. A shoulder 53 formed on the end of the plunger portion 44, between it and the hammer portion 42, is adapted to normally engage and seat on the bottom surface 54 of the bore 41 in the casing 25 when the plunger 39 is in its forward position and at rest, as shown in Figure 1. When the plunger 39 is in such position the camming shoulder 46,

or 47, as the case may be, is out of engagement with the pin 48.

The plunger 39 is counterbored out at its end opposite the hammer portion 42, or rear end 55, to receive a relatively strong coiled compression spring 56 which is adapted to react between the bottom 57 of the counterbore portion 58 and a flat disc-like end 59 of a driving member 61. The driving member 61 has a shank 62 extending rearwardly from the disc-like end 59 to be received and tightly clamped in the jaws of the chuck 15. The member 61 also has oppositely directed tongues 63 and 64 extending radially therefrom, which are adapted to enter, and to slide axially in, corresponding slots 65 and 66 provided in the plunger 39 and extending inwardly from the rear end thereof. The tongues 63 and 64 extend outwardly to closely adjacent the periphery of the plunger 39 and have their rear surfaces 67 and 68 engaged by a split single coil spring 69 seated in an annular groove 71 formed in the periphery of the plunger 39 adjacent its rear end 55. The spring 69 constitutes the means to hold the driving member 61, spring 56, and the plunger 39 together for assembly, as a unit, to the chuck 15.

The tool 24 is provided with a shank 72 adapted to enter a bore portion 73 in the stem 26 and have its inner end 74 abruptly engaged by the outer end 75 of the hammer portion 42 under the urge of the spring 56, when the pin rotates off of the high point 60 of either of the camming shoulders 46 or 47, and thereby produce a sharp blow upon the work at the cutting edge 76 of the tool 24. The tool shank 72 is provided with an axially elongated annular groove 77 in which a pin 78, slidably mounted in the stem 26, is adapted to lie to catch and retain the tool 24 in the stem 26. The pin 78 is constantly urged inwardly by a split flat ring-shaped spring 79, which partially encircles the stem 26 and overlies the outer end of the pin 78.

The tool inner end 74 is normally maintained out of contact with the hammer portion end 75, see Figure 1, by a spring pressed pin 84, which engages a rearwardly facing shoulder 82 formed between the shank 72 and the body 83 of the tool, which body 83 is made somewhat larger in diameter than the tool shank 72 for this purpose. The arrangement is such that the pin 78 engages the rear shoulder 84 of the annular groove 77 and prevents the tool shank 72 from dropping out of the stem 26. The pin 78 also limits the amount the shank end 74 is spaced out of contact with the hammer portion end 75. The length of the tool shank 72 is such that the shoulder 82 is spaced from the outer end of the stem 26 a greater amount than the amount the ends 74 and 75 are spaced apart, so that the latter ends may be engaged in varying degree when the tool end 76 is pressed against the work and the plunger 39 is rotated, while the shoulder 82 and stem end will not engage.

From the above it is obvious that a portable power driven hammer has been provided which may be readily and securely connected to any power driven shaft 11, such as one journaled in a sleeve 19 and having a chuck 15 secured thereto, for efficient operation thereby, the shaft being one either extending from a motor, or otherwise. This advantage is obtained by the simple expedients of clamping the shank 62 of the driving member 61 into the chuck 15 on the shaft 11 and then slipping the casing 25 over the plunger 39, assembled to the member 61, and locking the

casing to the sleeve by the cooperating slots 33, 34 and lugs 35.

After connecting and assembling the device to the power driven shaft 11 and its supporting sleeve 19, power may be applied to drive the shaft 11, whereupon the plunger 39 will be rotated in the casing 25. Rotation of the plunger 39 will cause it, in this instance twice every revolution, to alternately slide rearwardly, by the cooperating action of the pin 48 and the camming shoulders 46 and 47, and abruptly forwardly, under urge of the spring 56, to impose hammer-like blows upon the tool end 14, and through the tool 26 to upon the work against which the tool has been pressed.

Due to the provision of the rotatable pin 48 which rides with minimum friction upon the camming shoulders 46 and 47, a minimum of power is required to drive the plunger 39. Likewise the wear at this point, due to friction, is negligible and easily compensated for by the simple expedient of replacing the pin 48 with a new and relatively inexpensive one.

Due to the cooperating arrangement of the plunger 39 and the driving member 61, as above described, no appreciable shock is transmitted to the shaft 11, which, should this shaft be the shaft of a motor or the like, might cause serious damage. When in operation, the reciprocating motion given the hammer portion 42 is directly and wholly transmitted to the tool 24, as the shoulder 53 is held against contact with the bottom 54 of the bore 41 due to the pressure exerted against the tool 24. Thus no appreciable power is absorbed and lost, nor is any shock sustained by the casing 25, or the shaft 11, as pressure upon the tool end 75 to press it against the work is obtained from the handle 14, through the casing 12 and 16, the chuck 15, the driving member 61, the spring 56, the plunger 39, the hammer portion 25. Passing as it does through the spring 56 any reacting shock imposed upon the plunger 39 will be considerably cushioned by this spring before it can be appreciably transmitted back to the casing 12, and thus no appreciable power is absorbed by the casing 12 and lost. Due to this floating arrangement of the plunger 39 when the tool 26 is pressed against the work the force of the blow given to the work may be varied under control of the operator, the more pressure applied causing a heavier blow, and the lesser pressure a lighter blow. Such an arrangement is particularly advantageous when the tool is used for carving, or any other work requiring a variation in the force of the blow.

While there has been shown and described herein, one form of an improved portable power driven hammer, it is to be understood that the invention may be embodied in other forms without departing from the spirit and essential attributes thereof. It is therefore desired that the present embodiment be considered in all respects as illustrative, and not restrictive, and it will be further understood that each and every novel feature and combination thereof, present in, or possessed by, the device herein disclosed, forms a part of the invention included in this specification.

What is claimed as new and for which it is desired to secure Letters Patent is:

1. In a portable power driven hammer, a casing having a bore, a plunger slidably mounted in the bore of said casing, said plunger having a camming shoulder at one end and a counterbore in its other end, means carried by said casing to ride on said camming shoulder, a driving mem-

ber in the bore in said plunger and being slidable axially therein, a spring in the bore in said plunger between said driving member and said plunger, said plunger having an axially directed slot through a side wall thereof and communicating with the bore therein, said driving member having a tongue thereon extending radially therefrom into the slot in said plunger to drivingly connect them, and means to drivingly connect said driving member to a power driven shaft.

2. In a portable power driven hammer, a casing having a bore, a plunger slidably mounted in the bore of said casing, said plunger having a camming shoulder at one end and a counterbore in its other end, means carried by said casing to ride on said camming shoulder, a driving member in the bore in said plunger and being slidable axially therein, a spring in the bore in said plunger between said driving member and said plunger, said plunger having an axially directed slot through a side wall thereof and communicating with the bore therein, said driving member having a tongue thereon extending radially therefrom into the slot in said plunger to drivingly connect them, and means to drivingly connect said driving member to a power driven shaft.

15 3. In a portable power driven hammer, a casing having a bore, a plunger slidably mounted in the bore of said casing, said plunger having a camming shoulder at one end and a counterbore in its other end, means carried by said casing to ride on said camming shoulder, a driving member in the bore in said plunger and being slidable axially therein, a spring in the bore in said plunger between said driving member and said plunger, said plunger having an axially directed slot through a side wall thereof and communicating with the bore therein, said driving member having a tongue thereon extending radially therefrom into the slot in said plunger to drivingly connect them, and means to drivingly connect said driving member to a power driven shaft.

20 4. In a portable power driven hammer, a casing having a bore, a plunger slidably mounted in the bore of said casing, said plunger having a camming shoulder at one end and a counterbore in its other end, means carried by said casing to ride on said camming shoulder, a driving member in the bore in said plunger and being slidable axially therein, a spring in the bore in said plunger between said driving member and said plunger, said plunger having an axially directed slot through a side wall thereof and communicating with the bore therein, said driving member having a tongue thereon extending radially therefrom into the slot in said plunger to drivingly connect them, and means to drivingly connect said driving member to a power driven shaft.

25 5. In a portable power driven hammer, a casing having a bore, a plunger slidably and rotatably mounted in the bore of said casing, said plunger having a tool striking portion at one end and a counterbore in its other end, and a slot extending transversely across the counterbored end, a driven member having a tongue axially slidably in the slot in said plunger, means on said plunger to retain said tongue in the slot in said plunger, and spring means reacting between said plunger and said driven member to urge said tongue toward said retaining means.

30 6. In a portable power driven hammer, a tool engageable hammer unit comprising a plunger having a camming surface at one end and a counterbore in its other end, a part slidable in the counterbore in, and drivingly connected to, said plunger, said part having a portion extending from said plunger and connectable to a rotatable shaft, a spring in the counterbore in said plunger to react between said part and said plunger, and releasable means carried by said plunger and adapted to be engaged by said part to normally retain said part against movement from said plunger by said spring.

7. In a portable power driven hammer, a tool engageable hammer unit comprising a plunger having a camming surface at one end and a counterbore in its other end, a part slidable in the counterbore in, and drivingly connected to, said plunger, said part having a portion extending from said plunger and connectable to a rotatable shaft, a spring in the counterbore in said plunger to react between said part and said plunger, and releasable means carried by said plunger and adapted to be engaged by said part to normally retain said part against movement from said plunger by said spring.

8. In a portable power driven hammer, a tool engageable hammer unit comprising a plunger having a camming surface at one end and a counterbore in its other end, a part slidable in the counterbore in, and drivingly connected to, said plunger, said part having a portion extending from said plunger and connectable to a rotatable shaft, a spring in the counterbore in said plunger to react between said part and said plunger, and releasable means carried by said plunger and adapted to be engaged by said part to normally retain said part against movement from said plunger by said spring, and a one-piece casing adapted to be releasably connected to a shaft support and having a bore open at one end thereof, said casing carrying a rotatable pin and being adapted to freely slide over said hammer unit to disposed said pin in operative cooperation with

said camming surface and to slidably support said plunger upon the surface of its bore.

6. In a portable power driven hammer, a hammer unit comprising a plunger having a tool engaging end and a counterbore in its opposite end, a spring in the counterbore in said plunger, a part slideable in the counterbore in said plunger and having an abutment engaged by said spring, releasably cooperating means between said part and said plunger to drivingly connect said part to said plunger, means carried by said plunger to retain said cooperating means in operative position, and a spindle on said part adapted to be connected to a driven shaft and extending out of the counterbored end of said plunger.

7. In a portable power driven hammer, a casing having a hammer unit adapted to be readily removed from said casing by comprising a cylindrical plunger having a tool engaging end and a counterbore in its opposite end, a spring in the counterbore in said plunger, a part slideable in the counterbore in said plunger and having an abutment engaged by said spring, means on said part to drivingly connect said part to said plunger,

and a spindle on said part adapted to be connected to a driven shaft and extending out of the counterbored end of said plunger, said plunger having a portion of reduced diameter between its ends and a camming surface extending beyond the periphery of said portion, said casing adapted to be releasably connected to a shaft support and having a bore open at one end thereof, said casing carrying a rotatable pin and being adapted to freely slide over said hammer unit to dispose said pin at the reduced portion of the plunger in operative cooperation with said camming surface, and to slidably support said plunger within and upon the surface of its bore.

8. In a power driven hammer, a casing having a bore, a hammer plunger reciprocable in the bore in said casing, an extension on one end of said casing and having a bore, a tool shank slideable in the bore in said extension, a pin extending through said extension into an elongated slot in said tool shank, and a split spring band encircling said extension to resiliently hold said pin in place.

HAROLD F. MOSSBERG.
